UNITED STATES PATENT OFFICE

169,553

GIRDLE

Mario Laguzzi, New York, N. Y., assignor to Poirette Corsets, Inc., New York, N. Y.

Application January 23, 1953, Serial No. 23,275

Term of patent 14 years

(Cl. D20—2)

To all whom it may concern:

Be it known that I, Mario Laguzzi, a citizen of the United States of America, residing at New York city, in the county of New York, and State of New York, have invented a new, original, and ornamental Design for a Girdle, of which the following is a specification, reference being had to the accompanying drawing forming a part thereof.

In the drawing:

Fig. 1 is a front perspective view of a girdle showing my new design;

Fig. 2 is a rear perspective of the girdle shown in Fig. 1; and

Fig. 3 is a side view of the girdle shown in Fig. 1 as it appears when folded down the center of the front and rear panels, the opposite side presenting substantially the same appearance.

I claim:

The ornamental design for a girdle, as shown and described.

MARIO LAGUZZI.
